UNITED STATES PATENT OFFICE.

CHARLES PEARSON, OF CHICAGO, ILLINOIS, ASSIGNOR TO INTERNATIONAL HARVESTER COMPANY, A CORPORATION OF NEW JERSEY.

PITMAN CONNECTION.

1,424,935.

Specification of Letters Patent.

Patented Aug. 8, 1922.

Application filed February 26, 1919. Serial No. 279,439.

To all whom it may concern:

Be it known that I, CHARLES PEARSON, a citizen of the United States, residing at Chicago, in the county of Cook and State of Illinois, have invented certain new and useful Improvements in Pitman Connections, of which the following is a full, clear, and exact specification.

This invention relates to pitman connections for mowers and like machines.

The invention has among its objects to provide a construction by means of which a pitman may be easily and quickly connected to and disconnected from the element with which it co-operates.

A further object is to provide a connection by means of which the wear between the pitman and the co-operating element may be taken up, thereby providing an efficient operating connection between these parts.

In the embodiment of the invention illustrated, the pitman is provided with a pair of resilient straps and strap engaging members, means also being provided for manipulating the strap engaging members in such a manner as to force the straps toward each other into engagement with a bearing or co-operating element when the operating means is moved in one direction and to release the straps when the operating member is moved in the opposite direction.

The operating member is in this instance also so constructed and located with respect to the bearing member which is positioned between the outer ends of the pitman, that this operating member will engage the bearing member and force the pitman away from said member when the operating member is thrown to strap-opening position.

In the drawing I have illustrated one embodiment of my invention, and

Figure 1 shows a top plan view of the pitman connection, the straps being shown in clamping position;

Fig. 2 is a side elevation of the construction shown in Fig. 1, the open position of the operating member being shown in dotted lines; and

Fig. 3 is a top plan view of the construction shown in Fig. 1 with the clamping members and straps in open position, the operating member being shown partly in section in order to more clearly show the construction.

The body member 10 of the pitman, preferably made of wood, is of the usual construction, and this member has secured thereto at one end resilient pitman straps 11, which are secured by means of suitable rivets 12. The straps 11 are provided at their outer ends with semi-spherical bearing surfaces 13 adapted to engage with a bearing member 14 which in the case of a mowing machine is carried by the knife head. The outer surfaces of the end portions of the straps are provided with bearing surfaces 15 which co-operate with and are engaged by the outer ends of L-shaped strap-engaging members 16. The opposite ends 17 of the members 16 are cylindrical in outline and are received by angularly disposed sockets 18 formed in a barrel portion 19 of the operating member for the strap engaging and clamping members 16. The barrel portion 19 is rotatably mounted in the aligned apertures 20 formed in the pitman straps adjacent the bearing surfaces 13, and this barrel member has formed integrally therewith an operating lever 21 having a rear end portion 22 which seats on the upper surface of the pitman straps when the operating member is in clamping position. A central portion 23 of the operating member is adapted to engage the spherical bearing member 14 when the operating member is thrown to strap-opening position, as shown in dotted lines in Fig. 2. If the operating member is further rotated in an anticlockwise direction beyond the dotted line position of Fig. 2, this member will force the ball or bearing member 14 from between the straps, thereby separating the pitman from the cooperating member.

In order to retain the cylindrical portions 17 of the L-shaped strap-engaging members 16 in the sockets 18, I have provided a series of leaf springs 24 which co-operate with each other, and by the engagement of the longest springs with the strap engaging members 16 retain these members in their sockets.

Particular attention is here called to the fact that the sockets 18 formed in the barrel portion 19 of the operating member are disposed with their longitudinal axes at an angle to the rotative axis of the barrel 19, and because of this angularity as the operating member 21 is thrown from the posi-

tion shown in full lines in Figs. 1 and 2 to the position shown in dotted lines in Fig. 2, and also shown in Fig. 3, the strap engaging portions of the members 16 are moved 5 through an angle from the position shown in Fig. 1 to the position shown in Fig. 3, thereby releasing the straps from their clamping position. The friction between the cylindrical portions 17 of the strap-engaging members 16 and the walls of the sockets 18 formed in the barrel portion 19 is sufficient to retain the members 16 in the barrel portion as the operating member is moved from open to closed position. If desired, suitable flanges may be formed on the edges of the straps to protect the springs 24 and the engaging member 16 from damage.

From the showing in Fig. 3, it will be seen that when the operating member is in 20 strap-opening position the springs 24 will press the members 16 into the sockets, and, as above explained, the friction between the members and the walls of the socket is sufficient to retain these members in such a 25 position that they will insure the proper engagement of the straps with the bearing-member 14 when the operating member is thrown to strap-closing position.

From the above description, it will be seen 30 that an exceedingly simple and efficient device is provided to accomplish the purposes desired, and it will be clear that by the use of this construction the pitman may be quickly and readily detached from the co-operating member, and that the wear between the pitman straps and the co-operating member may be compensated for.

While I have shown and described a specific embodiment of my invention, it is to 40 be understood that it is capable of modification. Changes, therefore, in the construction and arrangement of parts may be made which do not depart from the spirit and scope of the invention as disclosed in the 45 appended claims.

Claims:

1. In a pitman connection, a pitman having resilient straps, a plurality of strap-engaging members contacting with said straps, and means for changing the angle of said members substantially in a plane at right angles to the plane of said straps, thereby forcing the straps toward each other and releasing said straps.
2. In a pitman connection, a pitman having resilient straps, a plurality of L-shaped strap-engaging members contacting with said straps, and means for changing the angle of said members with respect to said straps, thereby forcing the straps toward each other and releasing said straps.
3. In a pitman connection, a pitman having resilient straps, a plurality of members engaging said straps, an operating member 65 pivoted on said straps and loosely carrying

said engaging members, and means for holding said engaging members in position on said operating member.

4. In a pitman connection, a pitman having resilient straps, an operating member 70 journaled on said straps, strap-engaging members rotatably mounted in said operating member, the axes of rotation of said strap-engaging members being angularly disposed with respect to the axis of rotation 75 of said operating member.

5. In a pitman connection, a pitman having resilient straps, an operating member journaled on said pitman, strap-engaging members rotatably mounted in said operating member, the axes of said strap-engaging members being so disposed with respect to the axis of rotation of said operating member that said members will force said straps toward each other as said operating member 80 is moved in one direction about its axis, and will release said straps as the operating member is moved in the opposite direction about its axis.

6. In a pitman connection, a pitman having resilient straps, an operating member having a barrel portion journaled on said straps and the said barrel portion having outwardly extending sockets, the axes of 90 said sockets being angularly disposed with respect to the axis of rotation of said barrel portion, and strap-engaging members having portions seated in the sockets of said barrel portion of said operating member.

7. In a pitman connection, a pitman having resilient straps, an operating member having a barrel portion journaled on said straps and the said barrel portion having outwardly extending sockets, the axes of 100 said sockets being angularly disposed with respect to the axis of rotation of said barrel portion, strap-engaging members having portions seated in the sockets of said barrel portion of said operating member, and means for retaining said strap-engaging 105 members in said sockets.

8. In a pitman connection, a pitman having resilient straps, a strap engaging member for each strap having a shank portion and a strap-engaging portion, and means engaging said shank portions for actuating said members to force said straps toward each other.

9. In a pitman connection, a pitman having resilient straps, a strap engaging member for each strap having an angular shank portion, and a strap-engaging portion, and means engaging said shank portions for actuating said members to force said straps toward each other.

10. In a pitman connection, a pitman having resilient straps, strap controlling members having strap engaging portions, and means for oscillating said engaging portions toward each other.

11. In a pitman connection, a pitman having resilient straps, strap-controlling members having strap-engaging portions, and means for positively moving bodily said strap-engaging portions toward and away from each other.
12. In a pitman connection, a pitman having straps one of which is resilient, a member having a portion engaging said resilient strap, and means for oscillating said member bodily in such a manner as to force said resilient strap toward the other strap.
13. In a pitman connection, a pitman having straps one of which is resilient, a strap-controlling member having a portion engaging said resilient strap, and means for moving said strap-controlling member about a changing pivot in such a manner as to force said resilient strap toward the other strap.
14. In a pitman connection, a pitman having straps one of which is resilient, a strap-controlling member having a portion engaging said resilient strap, and means for moving said member bodily in such a manner as to positively force said resilient strap toward and away from the remaining strap.
15. In a pitman connection, a pitman having straps one of which is resilient, a strap-controlling member having a portion engaging said resilient strap, and an angular shank portion, and means engaging said
- shank portion for moving said member in such a manner as to force said resilient strap toward the remaining strap.
16. In a pitman connection, a pitman having straps one of which is resilient, a strap-controlling member having a portion engaging said resilient strap, and an angular shank portion, and means engaging said shank portion for moving said member about a changing pivot in such a manner as to force said resilient strap toward the remaining strap.
17. In a pitman connection, a pitman having resilient straps, a lever movable through substantially 180° relative to said straps, and strap engaging members movable relative to and controlled by said lever.
18. In a pitman connection, a pitman having resilient straps, strap-controlling members having strap-engaging portions, a lever pivoted to said straps, and means for positively moving said strap-engaging portions relative to said lever.
19. In a pitman connection, a pitman having resilient straps, a lever mounted in said straps, strap-engaging members for clamping said straps, and means for moving said strap-engaging members in a plurality of planes by said lever.

In testimony whereof I affix my signature.

CHARLES PEARSON.
